(57)

CLAIM

The ornamental design for a cooking pot, as shown and described.

DESCRIPTION

1.1: A perspective view of the cooking pot that is the subject of our invention;

1.2: Front elevation view thereof;

1.3: Back elevation view thereof;

1.4: Left side elevation view thereof;

1.5: Right side elevation view thereof;

1.6: Top view thereof;

1.7: Bottom view thereof;

1.8: Perspective view thereof with twisted top;

1.9: Perspective view as shown in 1.1 with handles down;

1.10: Front view thereof with handles folded down.

(Continued)

Features illustrated in broken line do not form a part of the claimed invention.

1 Claim, 10 Drawing Sheets
